US00D903685S

(12) **United States Design Patent** (10) **Patent No.:** **US D903,685 S**
Wright et al. (45) **Date of Patent:** **** Dec. 1, 2020**

(54) **ELECTRONIC CASE**

(71) Applicant: **CATALYST LIFESTYLE LIMITED**,
North Point (HK)

(72) Inventors: **Joshua Wright**, Hong Kong (CN);
June Lai, Hong Kong (CN)

(73) Assignee: **Catalyst Lifestyle Limited**, North Point
(HK)

(**) Term: **15 Years**

(21) Appl. No.: **29/685,901**

(22) Filed: **Apr. 1, 2019**

(30) **Foreign Application Priority Data**

Mar. 29, 2019 (CN) 2019 3 0139308

(51) **LOC (12) Cl.** **14-02**

Primary Examiner — Cynthia R Underwood

(74) *Attorney, Agent, or Firm* — Dinsmore & Shohl LLP

(57) **CLAIM**

The ornamental design for an electronic case, as shown and described.

DESCRIPTION

FIG. 1 is a perspective view including a front, an end, and a side of an embodiment of an electronic case;

FIG. 2 is a perspective view including a front, an end, and a side of an embodiment of an electronic case;

FIG. 3 is a perspective view including a front, an end, and a side of an embodiment of an electronic case;

FIG. 4 is a perspective view including a front, an end, and a side of an embodiment of an electronic case;

FIG. 5 is a planar view of the front of the electronic case of FIG. 1;

FIG. 6 is a planar view of the side of the electronic case of FIG. 1;

FIG. 7 is a planar view of an opposite side of the electronic case of FIG. 1;

FIG. 8 is a planar view of the end of the electronic case of FIG. 1;

FIG. 9 is a planar view of an opposite end of the electronic case of FIG. 1; and,

FIG. 10 is a planar view of a rear of the electronic case of FIG. 1.

1 Claim, 10 Drawing Sheets
